UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

STITCHED BUTTONHOLE.

Application filed December 24, 1927. Serial No. 242,382.

This invention relates to stitched buttonholes and has for an object to provide a buttonhole which has the appearance of a hand-made buttonhole, yet may be made by a buttonhole sewing machine. Another object of the invention is to provide a machine-made buttonhole, the slit of which is better covered with fewer stitches than heretofore.

To the attainment of the ends in view, a seam having the same thread-loop structure and concatenation as that shown in the patent to Allen et al., No. 1,372,473 of March 22, 1921, has been selected and modified by passing each slit-stitch needle-loop through the work in the same vertical plane, normal to the slit, of the preceding depth-stitch needle-loop; preferably carrying the ascending limb of the slit-stitch needle-loop forwardly in drawing it over the cut edge of the slit, preparatory to making a depth-stitch, so that such ascending limb will lie at an angle to the descending limb, giving to the needle-thread-lengths in the slit a spread or saw-tooth arrangement effectively covering the cut threads of the body-material, and particularly, of the interlining. The carrying forwardly of the ascending limb of the slit-stitch needle-loop at an angle to the descending limb, causes it to be laid over the edge of slit at a point even with the ensuing depth-stitch, so that the needle-thread length on the face of the material from such edge to the depth-stitch will tend to lie substantially normal to the buttonhole-slit. In the present buttonhole, the needle-thread lengths showing on the reverse face and, in fact, on both faces, of the material tend to lie in parallel arrangement and normal to the buttonhole slit, giving the buttonhole the appearance of a hand-made buttonhole. Furthermore, it is found that the purl of a buttonhole made in accordance with the present improvement has the twisted or ropy appearance characteristic of the purl of a hand-made buttonhole.

In the accompanying drawings Fig. 1 is a perspective view of the stitched buttonhole overseam showing the thread-structure and loop-concatenation. Fig. 2 is a "right" side or front face view of the buttonhole. Fig. 3 is a reverse face view, and Fig. 4 is a section on the line 4—4, Fig. 3.

According to the present improvement, the buttonhole comprises the body-material 1,

which includes the main plies 2 and interlining 3 in which is cut the buttonhole-slit 4. The needle-thread 5 is formed alternately into depth-stitch loops 6 and slit-stitch loops 7 which pass from one to the other face of the body-material. The limbs of each depth-stitch loop 6 lie close together from the point 8 where the depth-stitch is made, to the point 9 where the loop 6 emerges from the material. The limbs of the loop 6 extend from the point 9 to the slit 4 in a direction normal to the slit, each loop 6 being entered at the slit by the following loop 7, as shown in Fig. 1.

The looper-thread 10 is formed into loops 11 which pass through the loops 7 and are, in turn, entered by the loops 6; the arrow in Fig. 70 showing the direction in which the stitching progresses.

As the slit-stitch loop 7 is passed through the work at a point even with the preceding depth-stitch, it follows that the needle-thread 75 length 12 on the reverse face of the material between the point 8 and the edge point 13 lies normal to the buttonhole-slit. Also, the descending limb 14 of the slit-stitch needle-loop 7 lies in the vertical plane of the depth-stitch loop and thread-length 12; the loop 6, thread-length 12 and limb 14 forming a rectangle in a plane normal to the buttonhole-slit.

The ascending limb 15 of the needle-loop 85 7 does not lie vertically alongside of the limb 14 but is extended forwardly at an angle to the limb 14 from the point 15 to the point 13' which is even with the point of entry 8' of the ensuing depth-stitch needle-loop. 90 Thus, the needle-thread length 16 extending from the slit 4 to the depth-stitch loop is normal to the buttonhole-slit and parallel to the thread-length 12.

The purl 17 of the present buttonhole has 95 the characteristic twisted or ropy appearance of a hand-made buttonhole not heretofore attained in a machine-made buttonhole.

It will be seen that the needle-thread lengths on both faces of the material lie in groups of two or in spaced pairs substantially normal to the buttonhole slit. Also, the needle-thread lengths 12 and 16 on the reverse face of the material lie substantially in parallelism, instead of in zigzag formation, as 105 heretofore.

The present buttonhole is the product of the machine described in my co-pending ap-

plication Serial No. 242,381, filed herewith.

Having thus set forth the nature of the invention, what I claim herein is:—

1. In a stitched buttonhole, a body fabric formed with a buttonhole-slit, and an over-seam covering the material adjacent said slit and comprising a needle-thread formed into alternate depth-stitch and slit-stitch loops passing from one to the other face of the material, means for keying such loops, one limb of each slit-stitch loop lying in the vertical plane passing through the previous depth-stitch loop normal to the buttonhole-slit, and the other limb of such loop extending at an angle to the first-mentioned limb between the planes of the faces of the material. 10
2. In a stitched buttonhole, a body-fabric formed with a buttonhole slit, and an over-seam covering the material adjacent said slit and comprising a needle-thread formed into alternate depth-stitch and slit-stitch loops passing from one to the other face of the material, means for keying such loops, one limb of each slit-stitch loop lying in the vertical plane passing through the previous depth-stitch loop normal to the buttonhole-slit, and the other limb of such loop extending at an angle to the first-mentioned limb between the planes of the faces of the material. 20
3. In a stitched buttonhole, a body-fabric formed with a buttonhole-slit, and an over-seam covering the material adjacent said slit and comprising a needle-thread formed into alternate depth-stitch and slit-stitch loops passing from one to the other face of the material, means for keying such loops, one limb of each slit-stitch loop lying in the vertical plane passing through the previous depth-stitch loop normal to the buttonhole-slit, and the other limb of such loop extending at an angle to the first-mentioned limb between the planes of the faces of the material, the needle-thread lengths on the one face of the material lying substantially in parallelism. 30
4. A stitched buttonhole comprising a body-fabric formed with a buttonhole-slit, and an overseam covering the material adjacent said slit, said overseam including a needle-thread formed alternately into depth-stitch and slit-stitch needle-loops, the depth-stitch needle-loops passing vertically through the material at a distance from the slit and extending from the points of emergence to the slit in a direction normal to the latter, each of said depth-stitch needle-loops being entered and keyed by the succeeding slit-stitch needle-loop, the descending limb of each slit-stitch needle-loop lying in the vertical plane of the depth-stitch needle-loop which is normal to the buttonhole-slit, and a looper-thread formed into loops entering the slit-stitch needle-loops and being entered by the succeeding depth-stitch needle-loops. 40 50 55 60 65

alternate depth-stitch and slit-stitch loops passing from one to the other face of the material, means for keying such loops, one limb of each slit-stitch loop lying in the vertical plane passing through the previous depth-stitch loop normal to the buttonhole-slit, and the other limb of such loop extending at an angle to the first-mentioned limb between the planes of the faces of the material, the needle-thread lengths on both faces of the material lying substantially normal to the buttonhole-slit. 45

In testimony whereof, I have signed my name to this specification.

EDWARD B. ALLEN.
